UNITED STATES PATENT OFFICE

MILTON B. REACH, OF SPRINGFIELD, MASSACHUSETTS, ASSIGNOR TO A. G. SPALDING & BROS., OF NEW YORK, N. Y., A CORPORATION OF NEW JERSEY

GOLF CLUB

Application filed October 28, 1929. Serial No. 403,039.

My said invention relates to improvements in golf clubs of the type provided with tubular steel shafts and aims to provide improved means for reinforcing the shaft at a desired 5 point or points.

In the use of clubs provided with such shafts it has been found that the portion of the shaft adjacent the top end of the hosel receives the first and hardest shock of the blow 10 and that the steel shaft not infrequently breaks at this point.

It has been further noted that the preferences of golfers vary with respect to the location of suppleness or flexibility in a shaft, 15 as some like points of "feel" under or adjacent the grip, while others like the shaft fairly stiff under the grip end with the "feel" or suppleness lower down, between the lower end of the grip and the top of the hosel.

20 The present invention aims to provide a reinforcement for the shaft of standard make comprising a tubular member which is tapered uniformly from the grip end to the club head end, and which reinforcement will 25 be economical of manufacture and application and capable of being easily applied to the shaft to reinforce it at the desired point, and the invention includes the novel construction hereinafter described and defined by the 30 appended claims.

In the accompanying drawing I have shown the invention embodied in a club of the "iron" type embodying a steel head and tubular steel shaft which now customarily employ 35 a rubber sleeve interposed between the shaft and hosel to secure torsional resilience as is well understood by those skilled in the art, but this is shown by way of example only and my invention is not to be regarded as limited 40 to this type of club.

In the accompanying drawings:

Figure 1 is a view partly in section and partly broken away showing a club head and a sufficient portion of the shaft to illustrate 45 the invention;

Figure 2 is a detail view of the reinforcing sleeve;

Figure 3 is a view of a shaft with the reinforcement applied to a different portion 50 thereof; and

Figure 4 is a detail view of ferrule modified for this use.

In this drawing, 1 designates the club head intended as aforesaid to be representative of any customary golf "iron" having the usual 55 hosel 1a, and 2 designates the tubular steel shaft inserted and held in the hosel with the rubber sleeve 3 interposed between the inner wall of the bore of the hosel and the exterior of the portion of the shaft which projects 60 within the bore.

Such shafts, as is well known, are usually of tapered form, tapering from the handle end uniformly towards or to the hosel engaging 65 end.

In order to avoid the breakage of the shaft at or adjacent the top end of the hosel, I provide a reinforcing sleeve 4 within the hollow lower end of the shaft which is made of (preferably), steel tubing of a taper corresponding 70 to the taper of the shaft so that it may be driven into the same to secure a tight fit. While the frictional engagement due to the drive insert in most cases will effectually retain the sleeve in proper position, as there is 75 considerable vibration set up under the blow, I prefer to provide mechanical anchoring means for preventing any possible displacement, and the preferred manner of doing this is to effect a spot weld connection between the 80 sleeve and shaft. One such spot weld has been found amply sufficient.

The sleeve is made of such length that it (preferably), extends about an inch above and below the top end of the hosel, the area 85 of the club for about an inch being that which it is desired to strengthen.

To avoid any weakening effect on the shaft or tendency to breakage at the top end of the sleeve which might result if the upper end of the sleeve extended straight across perpendicular to its axis, I provide it with an irregular upper edge, preferably by providing such edge with a plurality of substantially V-shaped notches 4a forming intervening 90 tongues.

In tapered metal tubing such as used for the above purposes, there are liable to be irregularities in the taper and to compensate for this if desired, the thimble or sleeve 100

4 may be provided, before insertion, with a thin outer coating of soft metal or rubber which will accommodate itself to any irregularities in the interior surface of the shaft.

5 For the purpose of reinforcing the shaft at some other point as indicated in Figure 3, I provide the ferrule 5 which would have an external diameter corresponding to the internal diameter of the portion of the shaft 10 to be reinforced, and when such reinforcement was between the grip and hosel, the ferrule would have both ends provided with recesses and tongues as indicated at 5X Figure 4.

15 Having thus described my invention what I claim is:

1. A golf club having a tubular metal shaft, and a metallic reinforcing sleeve of less length than the shaft snugly fitting therein; said 20 sleeve having an irregular end edge.

2. A golf club having a tubular metal shaft, and a metallic reinforcing sleeve of less length than the shaft snugly fitting therein; and provided with substantially V-shaped 25 recesses forming intervening tongues.

3. The combination with a golf club having a tubular metal shaft engaging the bore of the head thereof, of a metallic reinforcing sleeve within said shaft and extending above 30 and below the top end of the hosel, said sleeve having an irregular upper edge.

4. The combination with a golf club having a tubular metal shaft engaging the bore of the head thereof, of a metallic reinforcing 35 sleeve within said shaft and extending above and below the top end of the hosel, said sleeve having substantially V-shaped recesses in its upper end providing intervening tongues.

5. The combination with a golf iron having 40 a tapered tubular metal shaft engaging the bore of the hosel of the head, of a metal sleeve of corresponding tubular form inserted in the shaft with a drive fit and positioned to extend above and below the top end of the hosel, 45 said sleeve having an exterior coating of softer material adapted to compensate for any irregularities in the tubing.

6. The combination with a golf club having a tubular metallic shaft of uniform tape of a 50 tapered ferrule of less length than the shaft having an exterior coating of softer material and inserted in the shaft with a drive fit.

In testimony whereof, I affix my signature.
MILTON B. REACH.
